UNITED STATES PATENT OFFICE.

REGINALD M. RANYARD, OF PALMS, CALIFORNIA, ASSIGNOR TO R. G. T. MFG. CO., OF LOS ANGELES, CALIFORNIA, A CORPORATION OF CALIFORNIA.

GAS FILTER.

Application filed September 4, 1924. Serial No. 735,887.

To all whom it may concern:

Be it known that I, REGINALD M. RANYARD, a citizen of the United States, residing at Palms, in the county of Los Angeles and 5 State of California, have invented new and useful Improvements in Gas Filters, of which the following is a specification.

This invention relates to improvements in gas filters.

10 It is an object of the invention to provide a suitable filter adapted to be readily inserted in a pipe line which will filter the gas passing therethrough and which is provided with a suitable baffle plate associated 15 with the filter so that particles of solid material and fluids may be separated out of the gas passing through the filter.

20 It is a further object of the invention to provide a gas filter which is simple and cheaply constructed and which has its parts so arranged that the filtering material may be easily and quickly withdrawn and replaced.

25 With the foregoing and other objects in view which will be made manifest in the following detailed description, reference is had to the accompanying drawings for an illustrative embodiment of the invention, wherein:

30 Figure 1 is a vertical section taken through the improved gas filter,

Fig. 2 is a horizontal section taken substantially on the line 2—2 of Fig. 1, and

35 Fig. 3 is a vertical section taken substantially on the line 3—3 of Fig. 1.

Referring to the accompanying drawings wherein similar reference characters designate similar parts throughout, the improved filter consists of a cylindrical shell 10 having an open top and about the upper edge of which is formed a suitable flange 11. A plate 12 is adapted to rest upon the flange 11 and to be secured thereto by means of bolts 13.

40 Upon one side of the shell 10 is formed a nipple 14 carrying a flange 15 adapted to be secured to the flange 16 of a pipe P by means of bolts 17. Gaskets 18 are preferably inserted between the flanges 15 and 16. 45 The nipple 14 which communicates with the interior of the shell 10 may be cast integral with the shell 10 or may be formed of a separate member and welded thereto.

Upon the opposite side of the shell 10 is secured a hemispherical chamber 19 which 55 communicates with the interior of the shell 10 and which may be secured by welding. The hemispherical chamber 19 is provided with an exhaust or discharge nipple 20 provided with a flange 21 adapted to be secured 60 to the flange 22 of a pipe P' by means of bolts 23. Suitable gaskets 24 may be inserted between the flanges 21 and 22. A plurality of arms 25 are secured interiorly of the hemispherical chamber 19 and extend 65 across the discharge opening formed by the nipple 20.

A fibrous filtering material 26 is placed in the hemispherical chamber 19 and is adapted to hold a screen 25^a against the arms 25. 70 A cylindrical receptacle 27 is adapted to be placed into the cylindrical shell 10 and is provided with an opening 28 adapted to register with the opening provided by the nipple 14. A larger opening 29 is formed 75 in the receptacle 27 adapted to register with the opening provided in the shell 10 by the hemispherical chamber 19. A section of wire screen 30 is adapted to be placed between the receptacle 27 and the shell 10 upon 80 that side of the shell 10 adjacent the hemispherical chamber 19 so that the screen 30 serves as a forward wall for enclosing the fibrous filtering material 26. A baffle plate 31 extends diametrically across the receptacle 27 and is welded thereto and extends downwardly from the top thereof to a point a short distance from the raised bottom 32 of the receptacle 27.

85 A suitable handhole 33 is formed in the baffle plate 31 to facilitate the withdrawal of the receptacle 27 from the shell 10 when it is desired to clean the filter and renew the fibrous filtering material 26.

The raised bottom 32 is provided with an aperture 32^a extending therethrough which communicates with a chamber 34 formed between the bottom of the shell 10 and the bottom 32 of the receptacle 27. An opening 35 is formed adjacent the bottom of the shell 10 and is interiorly threaded to receive a threaded plug 36. Water or other fluid which is separated from the gas flowing through the filter may pass through the aperture 32^a into the chamber 34 and to be 100 withdrawn therefrom upon removal of the 105

plug 36, a suitable opening 37 having been formed in the receptacle 27 to register with the opening 35 in the shell 10.

When the filter is inserted into a gas line 5 gas enters the filter through the pipe P, striking the baffle plate 31. Upon striking the baffle plate 31, water and particles of solid material are stopped and tend to fall to the bottom of the sleeve 27, the gas passing 10 downwardly and around the bottom of the plate 31 through the screen 30, the fibrous filtering material 26, and the screen 25^a, and is discharged through the pipe P'. A small quantity of gas passes through the 15 baffle plate 31 by means of the handhole 33. By providing the separate chamber 34 from the chamber above the bottom 32, the water separated from the gas will be kept out of contact with succeeding gas passing through 20 the filter.

When it is desired to clean the filter, it is merely necessary to remove the bolts 13 and the plate 12 and to withdraw the complete receptacle 27. This will lift out any particles of solid material which have collected 25 upon the bottom 32. The screen 30 may then be removed and the fibrous filtering material 26 can be withdrawn from the hemispherical chamber 19 and be replaced.

30 It is to be understood that various changes may be made in the detail of construction without departing from the spirit or scope of the invention as defined by the appended claims.

35 I claim:

1. A gas filter comprising a shell attachable to a pipe line, inlet and outlet openings formed in said shell, a removable container disposed within said shell, openings formed 40 in said container adapted to register with the inlet and outlet openings in said shell, and a baffle plate mounted in said container.

2. A gas filter comprising a shell attachable to a pipe line, inlet and outlet openings 45 formed in said shell, a removable container disposed within said shell, openings formed in said container adapted to register with said inlet and outlet openings in said shell, and a screen interposed between said container and said shell so as to cover said outlet opening.

3. A gas filter comprising a shell attachable to a pipe line, inlet and outlet openings 55 formed in said shell, a removable container disposed within said shell, openings formed in said container adapted to register with said inlet and outlet openings in said shell, a screen interposed between said container and said shell so as to cover said outlet opening, and a fibrous filtering material disposed in back of said screen.

4. A gas filter comprising a shell attachable to a pipe line, inlet and outlet openings 60 formed in said shell, a removable container disposed therewithin, openings formed in

said container adapted to register with said inlet and outlet openings, said container having a raised bottom with an aperture therein, said raised bottom forming a chamber between the bottom of said container 70 and said shell, and means for communicating with said chamber from the exterior of said shell.

5. A gas filter comprising a shell attachable to a pipe line, inlet and outlet openings 75 formed in said shell, a removable container disposed within said shell, openings formed in said container adapted to register with the inlet and outlet openings in said shell, and a baffle plate mounted in said container, 80 said baffle plate extending diametrically across said container and providing a passageway between itself and the bottom of said container.

6. A gas filter comprising a shell attachable to a pipe line, inlet and outlet openings formed in said shell, a removable container disposed within said shell, openings formed in said container adapted to register with the inlet and outlet openings in said shell, 90 a baffle plate mounted in said container, and a handhole formed in said baffle plate adjacent the top thereof to facilitate withdrawal of said container.

7. A gas filter comprising a shell adapted 95 to be inserted in a pipe line, inlet and outlet openings formed in said shell permitting gas to pass therethrough, a chamber forming the outlet opening, a screen disposed within said chamber, filtering material in said chamber, a container within said shell having openings adapted to register with said inlet and outlet openings, and a second screen interposed between said container and said shell adapted to cover said outlet opening.

8. A gas filter comprising a shell adapted to be inserted in a pipe line, inlet and outlet openings formed in said shell permitting gas to pass therethrough, a chamber forming the outlet opening, arms extending across said chamber, a screen disposed against said arms, filtering material within said chamber, a container within said shell having openings adapted to register with said inlet and outlet openings, and a second screen interposed between said container and said shell adapted to cover said outlet opening.

9. In a gas filter, a shell through which gas is adapted to pass, a container disposed within said shell, said container having a raised bottom cooperating with the bottom of the shell to form a chamber, an aperture formed in said raised bottom, and means for communicating with said chamber from the exterior of the shell.

10. A gas filter comprising a shell adapted to be inserted in a pipe line, inlet and outlet openings formed in said shell, the outlet opening being formed by a chamber upon

the side of the shell, a screen disposed over the outlet from said chamber, a second screen disposed over the inlet to said chamber, and filtering material between said screens.

11. A gas filter comprising a shell adapted to be inserted in a pipe line, inlet and outlet openings formed in said shell, the outlet opening being formed by a chamber 10 upon the side of the shell, a screen disposed over the outlet from said chamber, a second screen disposed over the inlet to said chamber, filtering material between said screens, and a removable baffle plate disposed 15 within said shell.

12. A gas filter comprising a shell having inlet and outlet openings formed therein, a removable container disposed within said shell having a raised bottom located some 20 distance below said inlet and outlet openings and defining a chamber therebelow, there being apertures formed in said bottom, and means whereby communication may be established between said chamber and the 25 exterior of the shell.

13. A gas filter comprising a shell having inlet and outlet openings formed therein, a removable container disposed within said

shell having a raised bottom defining a chamber therebelow, there being apertures 30 formed in said bottom, and means whereby communication may be established between said chamber and the exterior of the shell, said container carrying a baffle which is disposed between the inlet and outlet openings 35 in the shell.

14. A gas filter comprising a shell having inlet and outlet openings formed therein, means providing a removable lining within the shell having openings formed therein 40 adapted to register with the inlet and outlet openings in the shell, and a baffle carried by said lining which is arranged between the inlet and outlet to the shell.

15. A gas filter comprising a shell having 45 inlet and outlet openings formed therein, means providing a removable lining within the shell having openings formed therein adapted to register with the inlet and outlet openings in the shell, and a screen disposed 50 between the lining and the shell over one of said openings.

In testimony whereof I have signed my name to this specification.

REGINALD M. RANYARD.
